United States Patent Office

Des. 200,988
Patented Apr. 27, 1965

200,988

RADIOGRAPHIC EXPOSURE UNIT

Lawrence P. Feer, Cazenovia, N.Y., assignor to
Viso Corporation, Detroit, Mich.

Filed June 5, 1964, Ser. No. 80,305

Term of patent 14 years

(Cl. D83—1)

FIG. 1 is a left side elevational view of a radiographic exposure unit, showing my new design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof; and

FIG. 7 is a top perspective view thereof.

I claim:

The ornamental design for a radiographic exposure unit, as shown.
